UNITED STATES PATENT OFFICE.

ALBERT T. MAENCHE, OF WALTHAM, MASSACHUSETTS, ASSIGNOR TO JUDSON L. THOMSON M'F'G. CO., A CORPORATION OF MASSACHUSETTS.

RIVETING-MACHINE.

1,182,397.

Specification of Letters Patent.

Patented May 9, 1916.

Application filed May 29, 1914. Serial No. 841,935.

To all whom it may concern:

Be it known that I, ALBERT T. MAENCHE, a citizen of the United States, residing at Waltham, in the county of Middlesex and 5 State of Massachusetts, have invented new and useful Improvements in Riveting-Machines, of which the following is a specification.

This invention relates to a machine for 10 riveting pieces of sheet material together.

In riveting two pieces of sheet material together there is oftentimes a space between the adjacent surfaces of the said two pieces of sheet material before they are riveted 15 which it is desirable to close up before the rivet is clenched. Moreover, in clenching a rivet it is desirable that the head of the rivet should be firmly pressed against the outer surface of one of said pieces of sheet material before the clenching of the opposite 20 end of the rivet against the face of the other piece of sheet material begins. Otherwise, the rivet is liable to buckle between the end and the head and make an imperfect job in 25 this respect, and also it will begin to clench as soon as it passes the outer surface of the under piece of material and make a very small "curl over" in the clenching operation.

The desirable manner of performing the riveting operation is to position the rivet in the holes designed therefor in the two pieces of sheet material and clamp the two pieces of sheet material firmly together, with 30 the clenching end of the rivet projecting beyond the lower surface of the sheet metal plate against which it is to be clenched and then move the rivet while thus positioned and the metal plates which are to be riveted 35 together bodily toward an anvil, so that the entire amount of projection of the clenching end of the rivet shall be turned over or clenched against the face of the metal plate after the rivet has been positioned in the 40 plates and after the plates have been clamped firmly together.

It is the object of this invention to provide a machine which shall perform the riveting operation in the preferable manner 45 hereinbefore set forth.

The invention consists in the combination and arrangement of parts set forth in the following specification and particularly pointed out in the claims thereof.

50 Referring to the drawings: Figure 1 is

a front elevation of my improved riveting machine. Fig. 2 is a left hand side elevation of the same. Fig. 3 is a sectional elevation taken on line 3—3 of Fig. 1. Figs. 4, 5 and 6 are detail sectional elevations illustrating the relative positions of the parts during the riveting operation.

Like numerals refer to like parts throughout the several views of the drawings.

In the drawings, 10 is the frame of the 65 machine, 11 is the driving shaft journaled to rotate in suitable bearings 12 and 13 in the frame of the machine.

14 is a pinion fast to the driving shaft and meshing into a gear 15 which is journaled to rotate upon a shaft 16 and forms one member of a clutch 17. The other member 18 of said clutch is fastened to the shaft 16. The two members 15 and 18 are clutched together as one piece by suitable mechanism 70 (not shown in the drawings, but well known to those skilled in the art), this mechanism being operated from a treadle (not shown in the drawings) by means of a treadle rod 19.

The rivets are driven during the setting 80 operation by a driver 20 which is fastened to a slide 21 guided in ways 22 in the frame 10. The slide 21 has a vertical reciprocating motion imparted thereto by a pair of toggle links 23 and 24 which are connected 85 to a link 25 by a pivotal pin 26. The link 24 is pivoted at 27 to the frame of the machine, while the link 23 is connected to the upper end of the slide 21 by a pin 28. The link 25 is pivotally connected at its opposite 90 end to a crank-pin 29 which is fastened to a cam plate 30, said cam plate being in turn, fastened to the shaft 16. By this mechanism a reciprocating motion is imparted to the slide 21 and hence to the driver 20.

The rivets are fed from a hopper 31 down a raceway 32 and are separated by a slide 33 to be fed down a raceway 34 into a carrier 35 which consists of two carrier blocks 36 and 37 fast to springs 38 and 39, respectively, said springs being fastened by a bolt 40 to a carrier slide 41. The carrier slide 41 has a pin 42 fast thereto which projects through a slot 43 in the frame of the machine and constitutes a stop to limit the upward 100 movement of the slide 41. Said slide 41 also has a pin 44 fast thereto which projects into a slot 45 in the lever 46 which is pivoted at 47 to the frame of the machine and at its 105 opposite end is provided with a cam roll 110

48 which bears against the cam 30. A spring 49 is fastened at one end to the lever 46 and at the other end to the frame and acts to hold the roll 48 in engagement with the 5 cam 30 during its operation.

The rivets are transferred from the raceway 32 to the raceway 34 one at a time by the slide 33 which is operated by a lever 50 pivoted at 51 to the frame of the machine, and has a rocking movement imparted thereto in one direction by a spring 52 and in the opposite direction by a projection 53 on the rear side of the link 25. The operation of the slide 33 in transferring the rivets 15 from the raceway 32 to the raceway 34 is well known to those skilled in the art and, as it forms no part of this invention, requires no further description.

A stationary work-support 54 is mounted 20 in the outer end 55 of an arm 56 forming a part of the frame 10. This stationary work-support has embodied therein, or forming a part thereof, a recess 57 in its outer end, said recessed portion being shaped to turn 25 the end of the rivet outwardly and clench the same against the material, thus constituting an anvil. The outer upper edge 54' of the stationary work-support 54 constitutes a work-engaging surface while the 30 recessed portion 57 constitutes a clenching surface. The part 54, therefore, embodies a work-support with a work-engaging surface 54' and a clenching surface 57 constituting an anvil. Said stationary 35 work-support 54 is adjustable vertically toward and away from the driver 20 by means of an adjusting screw 58 having screw-threaded engagement with the arm 56 of the frame, being locked in adjusted position by means of a lock nut 59. Within the stationary work-support 54 is a spring 60, the lower end of which rests against a screw 61 having screw-threaded engagement with the stationary work-support 54, the upper 40 end of said spring bearing against a collar 62 upon a guide-pin 63, said guide-pin having sliding engagement with the upper end of the work-support 54 and being surrounded by the recessed portion 57 constituting 45 an anvil.

A movable work-support 64 forming a sleeve surrounds the upper end of the stationary work-support 54 and is supported by yielding means consisting, in the present 55 embodiment of my invention, of a lever 65 which is pivoted at 66 to a bracket 67 fast to the arm 56. The lever 65 is extended rearwardly from the pivot 66 and has a stop-screw 68 in screw-threaded engagement therewith. Said stop-screw projects below the lever 65 and is adapted to engage the upper edge of the arm 56 while being locked in position by means of a lock-nut 69. This adjusting means enables the work rest 64 to 60 be adjusted toward and away from the

driver bar 20. The rear end of the lever 65 has a hole 70 therein through which a rod 71 projects. The upper end of this rod is screw-threaded to engage nuts 72 and the lower end of said rod is provided with a 70 head 73 and washer 74 against which washer the lower end of a spring 75 bears. The upper end of said spring enters a recess 76 in the arm 56 and bears against the bottom of said recess. By adjusting the nuts 72, more 75 or less pressure by said spring can be brought to bear upon the rod 71 and thus upon the lever 65 to hold the stop-screw 68 against the arm 56 when pressure is brought to bear upon the upper end of the 80 sleeve work-support 64 for a purpose hereinafter more fully set forth. The sleeve work-support 64 has an ear 77 projecting downwardly from its lower edge into a corresponding notch 78 in the lever 65, thus 85 preventing the sleeve 64 from rotating relatively to said lever.

The rivets used in this embodiment of my invention are tubular rivets and the operation of riveting is illustrated in three steps 90 in Figs. 4, 5 and 6. As hereinbefore set forth, the rivets descend the raceway 34 and enter a chamber or pocket 79 between the carrier blocks 36 and 37. The work, consisting of a plurality of plates of sheet metal 95 80 and 81 which are to be riveted together, is placed upon the movable work-support 64 in the position illustrated in Fig. 4, with the under surface of the plate 81 resting against the upper edge of the movable work-support 64. In this position of the parts, which is the normal position of the work-support 64, it will be seen that the work-engaging surface or upper edge of said movable work-support lies in a plane between 100 the driver 20 and the work engaging surface of the stationary work-support 54. The guide-pin 63 at that time projects through two layers of sheet metal 80 and 81.

The tubular rivet 82, held in the pocket 110 79 of the carrier 35 and between the blocks 36 and 37, is moved downwardly by the lever 46 until the guide-pin 63 enters the bore of said tubular rivet, as illustrated in Fig. 4. The driver 20 at the same time is 115 moved downwardly by its slide 21 which is actuated as hereinbefore described by the toggle links 23 and 24 and the actuating link 25, crank-pin 29, cam 30 and shaft 16, and as said carrier and driver descend the 120 rivet is placed upon the upper end of the guide-pin 63 and is guided by said guide-pin through the holes 83 and 84 provided in the plates 80 and 81 and after the rivet is thus positioned the driver 20 continues to descend, pushing the rivet out from between the carrier blocks 36 and 37 and pushing the guide-pin 63 downwardly against the action of the spring 60 until the parts assume the relative positions illustrated in 125 130

Fig. 5, in which it will be noted that the rivet 82 has been pushed through the holes 83 and 84 in the plates 80 and 81 and that the under side of the head of said rivet bears 5 against the upper surface of the plate 80, while the end of the rivet which is to be clenched projects through the plate 81 a sufficient distance to be formed into a "curled over" clench by the final step in the 10 riveting operation, the plates 80 and 81 being clamped together. Up to this point the movable yieldingly supported work-support 64 remains stationary and is held in a stationary 15 position by the strength of the spring 75 which holds the rod 71 downwardly and holds the lever 65 in a stationary position until the plates 80 and 81 are clamped together by the driver 20, pushing the rivet head against the plate 80 and thus 20 clamping the plates 80 and 81 together, as hereinbefore set forth.

The operation of turning over the projecting end of the rivet is now performed by a further descent of the driver 20. It is evident 25 that upon a further descent of said driver 20 the plates 80 and 81, being firmly clamped together, cannot yield and the movable work-support 64 is obliged to move downwardly, being allowed so to do by reason 30 of the compression of the spring 75 through the intermediate elements, viz., the rod 71 and lever 65.

The spring 75 is constructed of such strength and the tension applied thereto is 35 such that said spring will take the thrust of the driver through the riveted plates until such time as said plates are firmly clamped together and the under side of the head of the rivet is firmly clamped against the upper 40 surface of the plate 80. Now, as the driver descends, as hereinbefore set forth, still further the projecting lower end of the rivet 82 encounters the curved depression 57 of the upper end of the work-support 54, 45 which constitutes an anvil and acts to "curl over" or clench that portion of the rivet which projects below the plate 81 and said clenched portion of the rivet is forced firmly against the under face of said plate 81, thus 50 firmly clamping and riveting the plates 80 and 81 together without any tendency to cramp the rivet 82 or to make it buckle prior to the clenching operation.

In the latter part of the riveting operation 55 it will be seen that the upper edge of the stationary work-support 54, outside the depression 57 constituting the anvil, forms a stationary work-support for the plates 80 and 81 and from the foregoing description 60 it will be seen that when the parts are in their normal positions the upper edge of the yieldingly supported work-support 64 is in advance of the work-engaging face of the stationary work-support 54 and so remains 65 until the clenching operation begins.

As soon as the plates have been riveted together, as hereinbefore described, the driver 20 moves upwardly releasing the pressure upon the rivet 82 and the plates 80 and 81. The movable work-support then 70 moves upwardly and the plates are removed from the guide-pin 63. The plates are then moved along by the operator and the guide-pin caused to enter another hole in readiness for the reception of another rivet and the 75 operation of the different parts hereinbefore described is repeated to feed, position and clenched another rivet.

While in the foregoing description and in the drawings, an embodiment of my invention 80 is described and illustrated particularly adapted for handling and setting tubular rivets, I do not wish to be understood as limiting my invention to the use of tubular rivets, as with very slight modifications 85 within the knowledge of one skilled in the art other forms of rivets can be used, fed and clenched without departing from the spirit of my invention.

Having thus described my invention, what 90 I claim and desire by Letters Patent to secure is:

1. A riveting machine having, in combination, a driver, an anvil, a work-support, a lever upon which said work-support is 95 mounted, a spring connected to said lever and adjustable means adapted to regulate the position of said lever and of said work-support relatively to said anvil and driver.

2. A riveting machine having, in combination, a driver, an anvil, a work-support, a lever upon which said work-support is mounted and adjustable means adapted to regulate the position of said lever and said work-support relatively to said anvil and 100 driver.

3. A riveting machine having, in combination, a movable work-support, yielding means upon which said movable work-support is mounted, a stationary work-support 110 adjacent to said movable work-support, an anvil adjacent to said work-supports and a driver movable toward and away from said work-supports, the work-engaging face of said movable work-support normally lying 115 in a plane between said driver and the work-engaging face of said stationary work-support and adjustable means constructed and arranged to regulate the position of said movable work-support relatively to said 120 anvil and driver.

4. A riveting machine having, in combination, a driver, a stationary anvil, a sleeve surrounding said anvil and constituting a work-support, a lever upon which said sleeve 125 is detachably mounted and a spring connected to said lever.

5. A machine for setting tubular rivets in a piece of sheet material having, in combination, a driver, a movable work-support, 130

yielding means upon which said movable work-support is mounted, a stationary work-support having a recessed portion constituting an anvil and a guide pin slidably mounted in said stationary work-support in alignment with said driver and surrounded by said recessed portion.

6. A machine for setting tubular rivets in a piece of sheet material having, in combination, a driver, a movable sleeve constituting a work-support, yielding means upon which said work-support is mounted, a stationary sleeve constituting a work-support, said stationary sleeve having a recess in one end thereof constituting an anvil and a guide pin slidably in said stationary sleeve in alignment with said driver and surrounded by said recessed portion.

7. A riveting machine having, in combination, a movable work-support, a yieldingly mounted lever upon which said movable work-support is mounted, a stationary work-support adjacent to said movable work-support, an anvil adjacent to said work-supports, a driver movable toward and away from said work-supports, the work-engaging face of said movable work support normally lying in a plane between said driver and the work-engaging face of said stationary work-support relatively to said anvil and driver, and independent adjustable means constructed and arranged to position said anvil and stationary work-support relatively to said driver.

ary work support, and means constructed 30 and arranged to adjust said lever, whereby the position of said movable work support relatively to said anvil and driver may be regulated.

8. A riveting machine having, in combination, a movable work-support, yielding means upon which said movable work-support is mounted, a stationary work-support adjacent to said work-supports, a driver movable toward and away from said work-supports, the work-engaging face of said movable work-support normally lying in a plane between said driver and the work-engaging face of said stationary work-support, 40 adjustable means constructed and arranged 45 to regulate the position of said movable work-support relatively to said anvil and driver, and independent adjustable means constructed and arranged to position said anvil and stationary work-support relatively 50 to said driver.

In testimony whereof I have hereunto set my hand in presence of two subscribing witnesses.

ALBERT T. MAENCHÉ
